To all whom it may concern:

Be it known that I, Dwight Powell, a citizen of the United States, residing at Youngstown, in the county of Mahoning and State of Ohio, have invented a new, original, and ornamental Design for a Chair, of which the following is a specification, reference being had to the accompanying drawing, forming part thereof:—

The figure is a perspective view of a chair showing my new design.

I claim:
The ornamental design for a chair as shown.

DWIGHT POWELL.
